DESIGN FOR A VAPORIZER OR SIMILAR ARTICLE

Charles W. Gibson, Chicago, Ill.

Application March 5, 1946, Serial No. 127,118

Term of patent 3½ years

(Cl. D83—1)

To all whom it may concern:

Be it known that I, Charles W. Gibson, a citizen of the United States and a resident of Chicago, in the county of Cook and State of Illinois, have invented a certain new, original, and ornamental Design for a Vaporizer or Similar Article, of which the following is a specification, reference being had to the accompanying drawing, forming a part thereof.

Figure 1 is a perspective view of a vaporizer or similar article showing my new design;

I claim:

The ornamental design for a vaporizer or similar article, substantially as shown.

CHARLES W. GIBSON.
